United States Patent Office

Des. 214,547
Patented July 1, 1969

214,547

HELMET

John Fisher, Dover, Del., assignor to ILC Industries, Inc.,
Dover, Del., a corporation of Delaware

Filed Mar. 29, 1968, Ser. No. 11,200

Term of patent 14 years

Int. Cl. D2—03

U.S. Cl. D2—232

FIG - 1

FIG - 3

FIG - 2

FIG - 4

FIGURE 1 is a front elevational view of a helmet showing my new design;

FIGURE 2 is a side elevational view thereof;

FIGURE 3 is a front elevational view with the face shield portion rotated to a position above the visor of the helmet; and

FIGURE 4 is a side elevational view thereof.

The face shield portion has been shaded for transparency.

I claim:

The ornamental design for a helmet, as shown and described.
